(57) CLAIM

We claim the ornamental design for a “gaming machine,” as shown and described.

DESCRIPTION

This application is related to U.S. Pat. application Ser. No. 29/186826 filed Jul. 23, 2003 and entitled “Gaming Machine,” and U.S. application Ser. No. 29/186825 filed Jul. 23, 2003 and entitled “Gaming Machine”.

FIG. 1 is an isometric view of a gaming machine showing our new design.

FIG. 2 is a front elevational view thereof.

FIG. 3 is a right side elevational view thereof.

FIG. 4 is a left side elevational view thereof.

FIG. 5 is a top plan view thereof.

FIG. 6 is a bottom plan view thereof; and,

FIG. 7 is a rear elevational view thereof.

The broken lines shown are for illustrative purposes only and form no part of the claimed design.
